William Knudson

UNITED STATES PATENT OFFICE.

TORKEL KNUDSON, OF MINNEAPOLIS, MINNESOTA.

DESIGN FOR A PHONOGRAPH-CABINET.

56,287.

Specification for Design.

Patented Sept. 14, 1920.

Application filed April 19, 1920. Serial No. 375,177. Term of patent 14 years.

To all whom it may concern:

Be it known that I, TORKEL KNUDSON, a citizen of the United States, residing at Minneapolis, in the county of Hennepin and State of Minnesota, have invented a new, original, and ornamental Design for a Phonograph-Cabinet, of which the following is a specification, reference being had to the accompanying drawing, forming a part

thereof, which shows the same in perspective.

I claim:

The ornamental design for a phonograph cabinet, as shown.

TORKEL KNUDSON.

Witnesses:

CLARA DEMAREST,
B. G. BAUMANN.
